(57) **CLAIM**

The ornamental design for a telephone handset, as shown and described.

DESCRIPTION

FIG. 1 is a front perspective view of a telephone handset;

FIG. 2 is a front view of the handset of FIG. 1;

FIG. 3 is a back view of the handset of FIG. 1;

FIG. 4 is a side view of the handset of FIG. 1;

FIG. 5 is an opposite side view of the handset of FIG. 1;

FIG. 6 is a top view of the handset of FIG. 1; and,

FIG. 7 is a bottom view of the handset of FIG. 1.

The portions drawn in broken lines are shown for illustrative purposes only and do not form part of the claimed design.

1 Claim, 3 Drawing Sheets
